STRANDING MACHINE

Guy Gilbert Greene, San Francisco, Calif., assignor to The American Steel and Wire Company of New Jersey, a corporation of New Jersey

Application May 3, 1935, Serial No. 19,723

10 Claims. (Cl. 117—20)

This invention relates to stranding machines such as are used in the wire rope art.

Such a machine conventionally includes a die, a rotary wire feeder associated with this die, a drive for this feeder, and a puller for pulling wires from the feeder through the die; and one of the objects of the present invention is to provide an improvement in the mechanical devices which inter-associate these various elements. Other objects may be inferred.

An example of a stranding machine embodying the principles of the present invention is diagrammatically illustrated by the accompanying drawings, in which:

Figure 1 is a plan showing a stranding machine of the type used to form stone sawing strand, the various mechanical devices which interassociate the conventional parts of this machine being spread out in the interests of clarity.

Figure 2 is a side elevation of the machine.

Figure 3 is a cross-section taken from the line III—III in Figure 1.

Figure 4 is a cross-section taken from the line IV—IV in Figure 1.

Figure 5 is a cross-section taken from the line V—V in Figure 1.

Figure 6 is a cross-section taken from the line VI—VI in Figure 1.

Figure 7 is a front view of the die.

Figure 8 is a section of this die from the line VIII—VIII in Figure 7.

Referring more particularly to the drawings:

The machine is conventional insofar as it includes a rotary frame 1 in which cradles 2 are pivoted so as to swivelly carry spools of wire 3, wire from the latter and from a swift 4 being led forwardly through a twister head 5 which rotates with the frame 1. This arrangement may be considered as constituting a rotary wire feeder which feeds a plurality of wires to a die 6, the wire being pulled through the latter by a draw-off drum 7 which may therefore be considered as constituting a puller. The particular construction of the die 6 and the character and arrangement of the mechanical devices which interassociate the various elements just described are, however, not conventional, and these form the subject matter of the present invention. The remainder of the specification is devoted to a disclosure of their character and function.

A motor 10 is coupled to a drive shaft 11 to which one of the planet gears 12 of planetary gearing is keyed. The epicyclic train 13 of this gearing is journaled in a cage 14, and the other

planet gear 15 of this gearing is keyed to a shaft 16.

The shaft 16 is keyed to gears 17 and 18, the former transmitting power to a pinion 19 by way of an idler gear 20, and the latter meshing directly with a pinion 21. Both pinions rotate freely on a shaft 22 to which a third pinion 23 is keyed. This pinion 23 may be coupled to either of the pinions 19 or 21 by means of clutches 24 and 25 which are under the control of a shaft 26. Furthermore, the pinion 23 meshes with a gear 27 which is connected to rotate the frame 1 and the twister head 5. This arrangement forms a reversing mechanism associated with the feeder.

A sleeve 28 has one end keyed to the cage 14, rotates freely on the shaft 16 and carries a gear 29 on its opposite end, this gear meshing with another gear 30 which is rotatively connected with a pinion 31. The latter meshes with a gear 32 which is carried by a sleeve 33 mounted by a shaft 34 for free relative rotation.

The sleeve 33 also carries a Geneva wheel 35 with which a Geneva cam 36 is associated. Figure 4 shows these last two elements, it being understood that Geneva elements are considered as constituting a star wheel whose projecting members 35^a are engaged by rollers 36^a carried on the opposite ends of a two-armed lever 36^b, whereby rotation of this lever causes the wheel to gradually accelerate and decelerate, while it holds the wheel stationary when in a position at right angles to any of the projections 35^a.

It follows that rotation of the frame 1 is effected in one direction or another, depending on the use of the clutches 24 and 25, as long as the cam 36 holds the wheel 35 stationary, since this holds the epicyclic train 13 stationary, the latter being that part of the planetary gearing whose rotative state determines the transmission of power from the rotary power source or motor 10.

A gear 37 is keyed to the shaft 11 and meshes with a gear 38 which is connected to a gear 39 which, in turn, meshes with a gear 40. The latter gear freely rotates on a shaft 41 to which it may be coupled through the medium of a clutch 42. This shaft 41 carries the cam 36, and it follows that rotation of this shaft upon operation of the clutch 42 will cause rotation of the epicyclic train 13, the arrangement being such that the latter is then rotated at a speed sufficient to prevent transmission of power to the shaft 16.

The clutch 42 includes an operating member 43 that is fixed to a reciprocative rod 44, the clutch and the member 43 being constructed and arranged so that reciprocation of the rod 44 towards

either of its extremes will couple the gear 40 to the shaft 41, while they will permit the gear 40 to rotate free of the shaft 41 when they are at a middle position. Springs 45 are provided to urge

5 the member 43 and rod 44 to this middle position.

A threaded shaft 46 is arranged parallel to the rod 44 and is in threaded engagement with an arm 47 which has an end that rides the rod 44 between the member 43 and an abutment 48^a, the latter being adjustably fixed to the rod 44. It follows that rotation of the shaft 46 in either direction will cause the arm 47 to move into engagement with either the member 43 or abutment 48^a, and that engagement with either will cause the gear 40 to be coupled to the shaft 41. This shaft 46 is driven by the shaft 22 through a gear train 48.

The shaft 26 is connected to the shaft 34 through a cam-and-lever arrangement 49 which 20 is constructed and arranged to reciprocate the shaft 26 sufficiently to alternately engage the clutches 24 and 25 upon half-turns of the shaft 34. That is to say, each time the shaft 34 turns a half revolution one of the clutches is engaged and the other disengaged, while when the shaft 34 turns another half revolution the first clutch is disengaged and the other engaged. Gears 41^a and 34^a interconnect the shafts 41 and 34 for dependent rotation. It is in this way that the reversing mechanism is controlled.

Operation of the mechanical devices which have been described so far is substantially as follows:

The motor 10 rotates the shaft 11 and the gear 35 40 and, assuming that the cam 36 is in a position which locks the epicyclic train 13 against revolving, a drive is effected through the planetary gearing and to the rotary wire feeder by way of the reversing mechanism. The rotative direction of the wire feeder is dependent upon which one of the clutches 24 and 25 are engaged. As rotation 40 of the rotary wire feeder proceeds, the gear train 48 rotates the shaft 46 until the arm 47 contacts either the member 43 or the abutment 48^a. This 45 effects reciprocation of the rod 44 and the member 43 so that the gear 40 is coupled to the shaft 41, which then rotates the cam 36.

The cam 36 then effects acceleration and deceleration of the wheel 35 to and from a rotative speed sufficient to cause the epicyclic train 13 to 50 revolve at a speed sufficient to prevent the transmission of power from the shaft 11 to the shaft 16, the rotary wire feeder therefore momentarily stopping.

55 Rotation of the shaft 41 also effects rotation of the shaft 34 which, in turn, effects rotation of the shaft 26 by way of the cam-and-lever arrangement 49. Since the various gears and their reversing mechanisms are at rest at this time, this 60 reversing action is effected without material wear on either of the clutches involved. This cam-and-lever arrangement 49 is so associated with the shaft 34 that operation of the reversing mechanism is effected at the time the wheel 35 is rotating at its maximum speed or, in other words, precisely at the time that the rotary wire feeder is at a standstill. Deceleration of the wheel 35 causes acceleration of the feeder, hence rotation 65 of the shaft 46 and consequently the release of the clutch 42, the parts being arranged to effect this to bring the cam 36 to locking position. The various parts thus effect a periodically reversing drive for the feeder.

70 As previously mentioned, a machine of the character described ordinarily includes a puller

for pulling the wires from the rotary wire feeder through the die 6, this puller consisting of the draw-off drum 7.

The mechanical devices for powering the draw-off drum will now be described:

The shaft 16 is keyed to the planet gear 50 of a planetary gearing whose epicyclic train 51 is mounted in a cage 52 which circumferentially carries a ring gear 53 that meshes with a pinion 54. The latter pinion is keyed to a shaft 55 10 which connects with the draw-off drum 7 through a suitable gear train 56. The other planet gear 57 of this planetary gearing is keyed to a shaft 58 which is also keyed to the planet gear 59 of another planetary gearing. The epicyclic train 60 15 of this other planetary gearing is mounted in a cage 61 which is kept from rotation by a lever 62, the latter being held by means of an articulated crank 63 having an adjustable connecting pin 63^a and which is keyed to the shaft 46. A rod 20 62^a interconnects this lever and crank.

The other planet gear 64 of this other planetary gearing is keyed to a shaft 65 which is connected to a second Geneva wheel 66 through gearing 67. This second Geneva wheel is engaged by a Geneva cam 68 that is connected to the shaft 34 by way of gearing 69. It is to be noted that the two last described planetary gearings are arranged in tandem so that control of the proper part of each will effect the control of the transmission of power 30 from the shaft 34, which may be considered as a rotary power source, to the draw-off drum or puller 7.

The operation of the additional mechanical devices now described is as follows:

As long as the rotary wire feeder is rotating at full speed in either direction, the shaft 46 will be rotated and the shaft 34 will be stationary. The arrangement of the cam 68 is such that it will lock the wheel 66 against movement at this time 40 so that the planet gear 57 will also be locked against free rotation. Therefore, the gear 53 will revolve so as to drive the shaft 55 and therefore the draw-off drum 7.

As soon as the wheel 35 revolves so as to effect 45 stoppage of the rotary wire feeder, the shaft 34 will start to revolve. The arrangement of the various parts is such that the cam 68 starts to revolve at a time when the wheel 35 is rotated at its maximum speed, and when the rotary wire 50 feeder is therefore at a standstill. Rotation of this cam 68 causes the wheel 66 to accelerate and decelerate and from a speed sufficient to rotate the planet gear 57 to a speed sufficient to prevent 55 the transmission of power through the planetary gearing driving the ring gear 53, and the draw-off drum 7 consequently ceases to rotate. Furthermore, the arrangement is such that the cam 68 comes to rest in a locking position respecting the wheel 66 as soon as the cam 36 comes to 60 rest in a similar position respecting the wheel 35.

It is apparent that deceleration and acceleration of the draw-off drum 7 is accomplished during the same period and by the same mechanism as the deceleration and acceleration of the rotary wire feeder and, furthermore, that the ratio of travel of the wires through the die would be constant throughout this period were it not for the action of the second Geneva wheel 66 and the 70 gearing 59, 60, 64, and 67 which can be arranged to permit a momentary loss of rotation of the draw-off drum 7 beginning at the instant the rotary wire feeder is motionless and continuing through sufficient acceleration of the rotary wire 75

feeder to allow proper reversal of the twist in the wires.

At this time it should be mentioned that the die 6 has a pass 6^a that is shaped to bend the wires beyond their elastic limits as they are pulled from the rotary wire feeder through the die by the puller. This is necessary to prevent untwisting or unloring of the wires during reversals of the rotary wire feeder.

0 It is now apparent that the machine is capable of producing a strand having a lay which reverses at definite intervals. The spacing of the reversals along the strand are, of course, determined by the ratios of the various gearings described, 15 these being variable by substitution to suit the demands of the product. In case it is desired to form a strand of regular lay, the gear 37 may be keyed to the shaft 11 through the medium of a clutch 11^a. When this clutch is disengaged and 20 the arm 47 is disengaged with the shaft 46, the various devices controlling the reversing mechanism and the planetary gearing that controls the drum 7 will be inoperative.

Continuing with the operation:

25 During the rotation of the rotary wire feeder in either direction the shaft 46 is rotated in one direction or another. Since this shaft 46 is connected to the arm 62 which locks the cage 61 of the planetary gearing associated therewith, 30 against rotation, through the medium of the articulated crank 63, the cage 61 will be slowly oscillated back and forth. The extent of this oscillation will depend upon the setting of the adjustable pin 63^a. Since this oscillatory movement effects the epicyclic train 60, it is apparent 35 that the rotary speed of the power transmitted will also oscillate. This means that the speed of the draw-off drum 7 will oscillate so that the pitch of the lay of the strand being formed by 40 the wires intertwisting in the die 7 will also vary. Thus, the machine is able to produce not only a strand that is of regular lay or reverse lay, but can produce a strand having a lay that gradually alternates from a long to a short pitch. This 45 type of strand has certain advantages in connection with its splicing, and forms the subject matter of a separate patent application.

Furthermore, it is to be noted that the machine 50 can produce a strand having a lay of uniform pitch simply by placing the connecting pin 63^a at the center of the articulated crank 63, in which case the cage 61 will be held stationary at all times so that the rotative speed of the power being transmitted through the associated planetary 55 gearing does not vary.

To remove the bend in the strands being formed by the particular shape of the pass in the die 6, straightening rolls 70 are arranged between the die 6 and the draw-off drum 7. These straightening rolls may be of any suitable design. The 60 particular design illustrated is covered by a separate application.

I claim:

1. In a wire stranding machine, the combination 65 of a die, a rotary wire feeder associated with said die, a periodically reversing drive for said feeder and means for pulling wires from said feeder through said die, the latter having a pass shaped to bend said wires beyond their elastic 70 limit as they are pulled therethrough.

2. In a wire stranding machine, the combination 75 of a die, a rotary wire feeder associated with said die, a reversing mechanism associated with said feeder, planetary gearing arranged to connect a rotary power source to said mechanism,

means for normally restraining rotation of a part of said gearing so as to permit the transmission of power from said source to said mechanism and for periodically rotating said part at a speed sufficient to prevent said transmission, 5 means responsive to operation of the first named means for controlling said reversing mechanism, and means for pulling wires from said feeder through said die.

3. In a wire stranding machine, the combination 10 of a die, a rotary wire feeder associated with said die, a periodically reversing drive for said feeder, a rotary puller arranged to pull wires from said feeder through said die, planetary 15 gearing arranged to connect a rotary power source to said puller, means responsive to reversals of said drive for normally restraining rotation of a part of said gearing so as to permit the transmission of power from said power source to said puller and for rotating said part at a speed sufficient 20 to prevent said transmission at least during said reversals.

4. In a wire stranding machine, the combination 25 of a die, a rotary wire feeder associated with said die, a drive for said feeder, a rotary puller arranged to pull wires from said feeder through said die, planetary gearing arranged to connect a rotary power source to said puller, and means for oscillating a part of said gearing so that the rotative speed of power transmitted to said puller 30 from said source is oscillatory.

5. In a wire stranding machine, the combination 35 of a die, a rotary wire feeder associated with said die, a reversing mechanism associated with said feeder, planetary gearing arranged to connect a rotary power source to said mechanism, a Geneva wheel arranged to control the rotation of a part of said gearing whose rotative state determines the transmission of power from said source to said mechanism, a Geneva cam associated 40 with said wheel, means for periodically rotating said cam at a speed sufficient to cause said wheel to accelerate and decelerate said part to and from a rotative speed sufficient to prevent said transmission, means responsive to rotation 45 of said cam for controlling said reversing mechanism and means for pulling wires from said feeder through said die.

6. In a wire stranding machine, the combination 50 of a die, a rotary wire feeder associated with said die, a periodically reversing drive for said feeder, a rotary puller arranged to pull wires from said feeder through said die, planetary 55 gearing arranged to connect a rotary power source to said puller, a Geneva wheel arranged to control a part of said gearing whose rotative state determines the transmission of power from said source to said puller, a Geneva cam associated with said wheel, and means responsive to reversals of said drive for rotating said cam at 60 a speed sufficient to cause said wheel to accelerate and decelerate said part to and from a rotative speed sufficient to prevent said transmission.

7. In a wire stranding machine, the combination 65 of a die, a rotary wire feeder associated with said die, a reversing mechanism associated with said feeder, planetary gearing arranged to connect a rotary power source to said mechanism, a Geneva wheel arranged to control the rotation 70 of a part of said gearing whose rotative state determines the transmission of power from said source to said mechanism, a Geneva cam associated with said wheel, means for periodically rotating said cam at a speed sufficient to cause 75

- said wheel to accelerate and decelerate said part to and from a rotative speed sufficient to prevent said transmission, means responsive to rotation of said cam for controlling said reversing mechanism, a rotary puller arranged to pull wires from said feeder through said die, planetary gearing arranged to connect a rotary power source to said puller, a Geneva wheel arranged to control the rotation of a part of the second named 10 gearing whose rotative state determines the transmission of power from the second named source to said puller, a Geneva cam associated with the second named wheel, and means for rendering responsive the second named cam to the first named cam so that rotation of the latter causes rotation of the second named cam at a speed sufficient to cause the second named wheel to accelerate and decelerate the second named part to and from a rotative speed sufficient to prevent the second named transmission.
8. In a wire stranding machine, the combination of a die, a rotary wire feeder associated with said die, a reversing mechanism associated with said feeder, planetary gearing arranged to connect a rotary power source to said mechanism, a Geneva wheel arranged to control the rotation of a part of said gearing whose rotative state determines the transmission of power from the said source to said mechanism, a Geneva cam associated with said wheel, means for periodically rotating said cam at a speed sufficient to cause 15 said wheel to accelerate and decelerate said part to and from a rotative speed sufficient to prevent said transmission, means responsive to rotation of said cam for controlling said reversing mechanism, a rotary puller arranged to pull wires from said feeder through said die, planetary gearing arranged to connect a rotary power source to said puller, a Geneva wheel arranged to control the rotation of a part of the second named 20 gearing whose rotative state determines the transmission of power from the second named source to said puller, a Geneva cam associated with the second named wheel, means for rendering responsive the second named cam to the first named cam so that rotation of the latter causes rotation of the second named cam at a speed sufficient to cause the second named wheel to accelerate and decelerate the second named part to and from a rotative speed sufficient to prevent 25 the second named transmission, the last named means being so timed that the second named cam starts to so rotate the second named wheel at the time the first named cam is rotating the first named wheel at its maximum speed, said die having a pass shaped to bend said wires beyond their elastic limit, another planetary gearing arranged to connect the second named source to said puller, the second and third named gearings being arranged in tandem, and means for oscillating a part of the third named gearing so that the rotative speed of power transmitted from the second named source to said puller is oscillatory.
10. In a wire stranding machine, the combination of a die, means for rotating wires and directing them through said die, a puller arranged to pull wires through said die and driving means for said puller adapted to drive the same at a periodically varying rate.

first named cam is rotating the first named wheel at its maximum speed, and said die having a pass shaped to bend said wires beyond their elastic limit.

9. In a wire stranding machine, the combination of a die, a rotary wire feeder associated with said die, a reversing mechanism associated with said feeder, planetary gearing arranged to connect a rotary power source to said mechanism, a Geneva wheel arranged to control the rotation of a part of said gearing whose rotative state determines the transmission of power from the second named source to said mechanism, a Geneva cam associated with said wheel, means for periodically rotating said cam at a speed sufficient to cause 15 said wheel to accelerate and decelerate said part to and from a rotative speed sufficient to prevent said transmission, means responsive to rotation of said cam for controlling said reversing mechanism, a rotary puller arranged to pull wires from said feeder through said die, planetary gearing arranged to connect a rotary power source to said puller, a Geneva wheel arranged to control the rotation of a part of the second named 20 gearing whose rotative state determines the transmission of power from the second named source to said puller, a Geneva cam associated with the second named wheel, means for rendering responsive the second named cam to the first named cam so that rotation of the latter causes rotation of the second named cam at a speed sufficient to cause the second named wheel to accelerate and decelerate the second named part to and from a rotative speed sufficient to prevent 25 the second named transmission, the last named means being so timed that the second named cam starts to so rotate the second named wheel at the time the first named cam is rotating the first named wheel at its maximum speed, said die having a pass shaped to bend said wires beyond their elastic limit, another planetary gearing arranged to connect the second named source to said puller, the second and third named gearings being arranged in tandem, and means for oscillating a part of the third named gearing so that the rotative speed of power transmitted from the second named source to said puller is oscillatory.
10. In a wire stranding machine, the combination of a die, means for rotating wires and directing them through said die, a puller arranged to pull wires through said die and driving means for said puller adapted to drive the same at a periodically varying rate.
